CLAIM

(57) The ornamental design for a charging base with portable power supply, as shown and described.

DESCRIPTION

FIG. 1 is a perspective view of the front, top and right side of a charging base with portable power supply showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof shown in a used condition.
